GENERATOR PROPELLER

Eddie J. Weible, Hillsboro, N. Dak.

Application April 12, 1935, Serial No. 16,069

1 Claim. (Cl. 170—68)

This invention appertains to new and useful improvements in propellers and more particularly to a propeller for use in conjunction with aircraft generators.

5 The principal object of the present invention is to provide a generator propeller of such construction that it will automatically change its blade pitch as the speed thereof increases.

Another important object of the invention is 10 to provide a generator propeller of simple construction and not susceptible to the development of ready defect.

These and various other important objects and 15 advantages of the invention will become apparent to the reader of the following specification.

In the drawings:

Figure 1 represents a front elevational view of the propeller.

Figure 2 represents a sectional view taken substantially on line 2—2 of Figure 1.

Figure 3 represents a fragmentary sectional view through the hub portion of the propeller.

Figure 4 represents a fragmentary front elevational view showing the hub with the cover 25 removed.

Figure 5 represents a sectional view taken substantially on line 5—5 of Figure 3.

Figure 6 represents an elevational view of one of the governor weights and gear assemblies.

30 Figure 7 represents a sectional view taken substantially on line 7—7 of Figure 1.

Figure 8 represents a fragmentary side elevational view of one end of one of the propeller shafts.

35 Referring to the drawings wherein like numerals designate like parts it can be seen that numeral 5 represents the hub plate which is rabbed as at 6 to receive the end portion of the deep cover like structure 7 which encases the 40 governor mechanism generally referred to as at 8. The propeller is of the type employing a pair of blades 9—9, each having a shank 10 provided with a hollow extension 11 slotted as at 12. Each of these slotted hollow extensions 45 11 engages over a corresponding countershaft 13 of the said governor mechanism 8, which shaft 13 is journaled through bearings 14—15 on the plate 5. Each shaft 13 has a quadrant gear 16 keyed thereto and the gears mesh in the manner 50 shown clearly in Figure 2. Each gear 16 has an

arm 17 extending outwardly therefrom and equipped at its outer end with a weight 18. A spring 19 of the coiled type connects the other end portion of the arm 17 while additional coiled springs 20 extend from points adjacent the outer 5 end of the arm 17 to suitable anchors 21 carried by opposite gears 16 keyed to the anchors 21 as in the form of a protuberance capable of being stopped by an outstanding stop member 22 on the hub 5 to limit the action of the governor 10 mechanism.

The bearings 14—15 are in the form of ball bearing mounts 23—as shown in Figure 5 while thrust collars 24 are provided on the ends of the shaft 13—13 at the said hub 5. 15

To maintain the propeller shank 10 connected to the corresponding shank 13 a split clamp 25 is employed and clamped around the slotted extension 11 through the use of bolts 26 so as to compress this portion 11 of the shank against 20 the counter shank 13.

Obviously as the assembly shown in Figure 1 rotates and speed increases, the weights 18 separate and in doing so rotate the shaft 13—13 in opposite directions to the end that the pitch of 25 the propeller blades will be changed.

While the foregoing specification sets forth the invention in specific terms, it is to be understood that numerous changes in the shape, size and materials may be resorted to without departing 30 from the spirit and scope of the invention as claimed hereinafter.

Having thus described the invention, what is claimed as new is:

A propeller of the class described comprising 35 a drive shaft, a hub on said drive shaft, a pair of parallel rotatably mounted shafts on the hub and provided with meshing gears, each gear being provided with an outwardly extending arm 40 having a weight at its free end thereof, the lower portion of each arm being provided with protuberances, stop means on said hub for cooperation with said protuberances for limiting the movement of said gears, extensible coiled springs 45 each connected at one end to one of the arms adjacent its outer end, said springs being connected at their opposite end to the protuberances from which the complementary arm extends, and blades at the outer ends of each shaft. 50
